UNITED STATES PATENT OFFICE.

OTTO C. WOLF, OF PHILADELPHIA, PENNSYLVANIA.

SUPPORTING STRUCTURE FOR TANKS.

No. 831,399.

Specification of Letters Patent.

Patented Sept. 18, 1906.

Application filed January 4, 1906. Serial No. 294,596.

To all whom it may concern:

Be it known that I, OTTO C. WOLF, a citizen of the United States, residing in Philadelphia, Pennsylvania, have invented certain improvements in Supporting Structures for Tanks, of which the following is a specification.

One object of my invention is to provide a structure for the reception and support of a number of tanks, commonly of cylindrical form, such as are employed in the storage or stock houses of breweries, which structure shall be of such a nature that it is relatively inexpensive and simple, with its parts so built and placed that there is little, if any, place for the accumulation of dirt, said parts being, moreover, so arranged that they may easily be kept clean and at the same time permit of the most economical utilization of the space available for the reception of the storage-tanks.

Another object of the invention is to provide a simple and convenient construction for supporting the individual tanks upon the various beams which are designed to carry them.

These objects I attain as hereinafter set forth, reference being had to the accompanying drawings, in which—

Fig. 1 is a vertical section of one floor of a building constructed according to my invention and showing, somewhat diagrammatically, a number of tanks in position therein. Fig. 2 is a fragmentary horizontal section of the upper portion of the structure illustrated in Fig. 1, further showing my invention. Fig. 3 is a front elevation of one of the structures for directly supporting the tanks on the beams of the building, and Fig. 4 is a side elevation of a portion of the structure shown in Fig. 3.

In carrying out my invention, I provide a building of suitable dimensions having within the space between its floors an open framework composed of a series of columns placed to support its floor and roof, as well as an intermediate skeleton floor consisting of one or more substantially horizontal frames formed of structural sections carried by the walls of the building and by said columns. The structural sections are of such dimensions and spacing that each tank is supported by two beams extending parallel to and at substantially equal distances from its longitudinal axis, there being provided for this purpose

suitable leg structures connected to each other in pairs and supporting the tanks upon said beams.

In the above drawings, A represents the wall of the building, which is designed to have a number of floors, of which the one illustrated is provided with means for supporting two tiers of horizontal tanks B or B', while a third series of tanks B² is placed within the basement or cellar. For the support of the tanks B and B', I provide a series of columns a, extending through the longitudinal center of the building and directly supporting the beams of the first floor a³. Said columns a also carry columns a⁹, which not only carry the roof or ceiling structure a', but also support an open-work floor formed of structural sections a⁴, secured to each other, but having their ends respectively carried by the walls of the building and by longitudinally-extending beams directly resting upon the columns a⁹.

The various tanks B, &c., are symmetrically placed with regard to each of the beams of the open-work floor—that is to say, each tank is placed over and carried by a pair of beams a⁴ in such manner that its center line is equidistant from and parallel with said beams, which are connected together by transverse sections a⁵.

The leg structures connecting the tanks and the beams upon which they are supported each consists of a foot-section a⁶, extended laterally at the base, so as to fit upon the flange of the beam a⁴, and provided with downwardly-extending edges or flanges whereby it is kept in position on said beam. The body of the foot-piece a⁶ is made tubular for the reception of one end of a screw a⁷, whose opposite end enters a suitably-threaded recess in a casting D, forming a saddle-piece which is shaped to receive one of the circumferential flanged portions or ribs b of the tank and which is, moreover, curved, so as to fit the cylindrical surface of said tank.

The members of each pair of the castings D are held together by means of a tie-rod d, threaded at its ends and extended through suitably-formed lugs upon the castings, wherein it is held by means of nuts, as shown. Each of the screws a⁷ is provided with a nut a⁸, whereby the piece D, carried by it, may be raised or lowered, so as to adjust the height of the tank.

With the above arrangement of parts I

place two rows of tanks in each tier in such manner that there is an open space or gallery between their adjacent ends, and in this open space I provide at each tier a concrete 5 gallery-floor a^2 , carried upon the open-work structure, it being understood that these walks or gallery-floors are preferably the only floor structures employed.

From the above it will be seen that the 10 arrangement of the supporting structures for the tanks B, &c., is of the simplest nature, so that while there is but little floor-surface capable of collecting dirt or objectionable germs even this is readily accessible 15 for purposes of washing. It will further be seen that the relative arrangement of the tanks is such that they are carried on the beams by very simple yet substantial supporting structures, so that the arrangement 20 as a whole is in the highest degree convenient and of a nature easily kept clean.

I claim—

1. A supporting structure for a tank including two substantially horizontal beams, 25 foot-pieces resting on each of the beams, and saddle-pieces formed to engage the cylindrical surface of the tank and carried by the foot-pieces, said foot and saddle pieces being placed upon the beams in pairs opposite one 30 another, with means for holding together

each pair of saddle-pieces, substantially as described.

2. The combination of a series of pairs of saddle-pieces designed to engage the cylindrical surface of a tank, and grooved for the 35 reception of ribs thereon, lugs on said saddle-pieces, a tie-bolt engaging said lugs and extending between the saddle-pieces of each pair, each saddle-piece having a threaded 40 downwardly-extending projection, a nut thereon, a tubular foot-piece for the reception of each of said projections, said foot-pieces being flanged to fit structural sections, substantially as described.

3. The combination of a building having a 45 series of columns and beams arranged to form an open floor extending from said columns to the walls of said building, means for supporting two series of tanks on the beams in such manner as to leave a passage between 50 their adjacent ends, and a relatively narrow gallery-floor for said passage, substantially as described.

In testimony whereof I have signed my name to this specification in the presence of 55 two subscribing witnesses.

OTTO C. WOLF.
